UNITED STATES PATENT OFFICE.

ROGER W. CLIFFORD AND PHILIP J. NICHOLS, OF SCHENECTADY, NEW YORK.

THROTTLE-VALVE.

1,338,489.

Specification of Letters Patent. Patented Apr. 27, 1920.

Application filed October 2, 1919. Serial No. 327,949.

To all whom it may concern:

Be it known that we, ROGER W. CLIFFORD and PHILIP J. NICHOLS, both of Schenectady, in the county of Schenectady and State 5 of New York, have jointly invented a certain new and useful Improvement in Throttle-Valves, of which improvement the following is a specification.

Our invention relates to means for controlling the flow of fluids, and more particularly to single seated throttle valves of the balanced type for locomotive engines, although not limited in application thereto. The object of the invention is to provide 15 a valve of the above type which shall embody the advantages of simplification of construction, reduction of compass, and promotion of the unobstructed flow of steam when unseated.

20 The improvement claimed is hereinafter fully set forth.

In the accompanying drawings: Figure 1 is a vertical central section through a throttle valve, illustrating an embodiment 25 of our invention, the valve being shown as seated; Fig. 2, a view, the upper half of which is a horizontal section through the hood, with the valve removed, taken on the line *a a* of Fig. 1; Fig. 3, a vertical central 30 section, taken at a right angle to Fig. 1, the valve being shown as unseated; Fig. 4, a similar section, illustrating a structural modification; and, Fig. 5, a horizontal section, on the line *b b* of Fig. 4.

35 In single seated throttle valves of the balanced type, the balancing piston is usually made a part of the main valve and located within a balancing chamber. In passing a valve of such construction, the steam 40 necessarily passes through and around the balancing chamber, and is thereby deflected at sharp angles, and its flow impeded. The balancing chamber is, of course, larger than the main valve, and, by reason of its weight 45 and the machining of its finished surfaces, it becomes one of the most costly members of the complete valve structure. The objections above noted will be found to be eliminated by our improvement herein set forth.

In the practice of our invention, referring descriptively to the specific embodiment

ment thereof which is herein exemplified, and first to Figs. 1 to 3 inclusive, we provide an open topped hood or casing, 1, 55 which, in this instance, is secured, detachably, by bolts, 1^a, and nuts, to the top of the stand pipe, 2, through which steam passes from the boiler to the cylinders of a locomotive, the joint between the hood and pipe being made steam tight by grinding or by suitable packing. An opening, corresponding in diameter with the inside of the stand pipe, is formed in the bottom of the hood, and a beveled or conical valve 60 seat, 1^b, is machined at the top of said opening. While the hood is herein shown as formed separately from, and detachably connected to, the stand pipe, it may, if preferred, be cast integral therewith, its functions being to provide a guide for the throttle valve in the traverses of the latter, and to enable steam to be taken at the highest level of the steam dome of the boiler.

A cylindrical throttle valve, 3, of the puppet type, which is bored out truly on its inner surface, is fitted to seat upon the valve seat, 1^b, and thereby to control the passage of steam, through the hood, from the boiler to the stand pipe. The throttle valve is 75 raised and lowered, from and to its seat, by connections to any suitable known valve operating mechanism, which does not, in and of itself, form part of our invention, and is not, therefore, herein set forth. The 80 valve operating mechanism is connected to a pair of vertical rods, 4, 4, to the upper ends of which there is secured a cross head, 5, which is coupled by a pin, 5^a, to the upper end of a valve stem, 6, connected, with 85 the capacity of a limited degree of relative movement, to the throttle valve, 3. The periphery of the throttle valve carries annular flanges, 3^a, fitting against vertical ribs, 1^c, on the wall of the hood, said ribs 90 serving to guide the valve in its traverses toward and from its seat.

A cover plate, 3^b, closes the throttle valve at its top, and is detachably secured to it, by studs, 3^c, a ground joint being made between the cover plate and valve, to prevent leakage of steam into the latter. The 100 interior of the throttle valve constitutes a balancing chamber, in which is neatly fitted

a balancing piston, 7, which is provided with water grooves or suitable packing on its periphery, in order to make a tight joint with the wall of the inclosing balancing chamber. When the throttle valve is seated, as shown in Fig. 1, the balancing piston abuts against the bearing lugs, 2^a, on the inside of the stand pipe, and when the valve is unseated, as shown in Fig. 3, it rests on shoulders, 3^a, on the wall of the balancing chamber.

The valve stem, 6, which passes freely through the throttle valve and balancing piston, and is, as before stated, coupled to the cross head, 5, has, formed upon or secured rigidly to it, a pilot valve, 8, of the beveled face puppet type, which is fitted to seat upon a correspondingly formed face surrounding an opening in the cover plate, 3^b, and thereby to control the admission of steam from the hood to the balancing chamber. The upward or unseating movement of the pilot valve, independently of the throttle valve, is limited by a tappet, in the form of a nut, 6^a, screwed upon the valve stem, 6, and adapted to abut against a bearing on the inner side of the cover plate. The valve stem and pilot valve are guided between lugs, 6^b, on the cover plate, which also serve as an abutment for the nut, 6^a.

In operation, the upward movement of the valve stem, 6, effected by the actuation of the operating mechanism for the purpose of unseating the throttle valve, preliminarily unseats the pilot valve, the throttle valve remaining on its seat, against which it is held by the pressure of the steam on the cover plate. The unseating of the pilot valve admits steam, from the boiler and hood, into the balancing chamber, in which its pressure acts downwardly upon the balancing piston, thereby holding it against the lugs, 2^a, and upwardly, with the same force, against the cover plate of the throttle valve. Equilibrium of pressure being thus instituted, on the opposite sides of the cover plate, the connected throttle valve is consequently balanced, and by the further movement of the valve stem, resultant upon the contact of the tappet, 6^a, with the lugs on the cover plate, it may be raised through the full extent of its traverse, without opposition by steam pressure resistance. The balancing piston being also balanced, is raised by and with the throttle valve, into the position shown in Fig. 3, and is returned to its normal position, in and by the seating of the throttle valve.

The structural modification illustrated in Figs. 4 and 5, accords, in all fundamental features of construction and operation, with the appliance shown in Figs. 1 to 3 inclusive and above described, differing therefrom principally in the particulars that a station-

ary balancing piston is, in this instance, applied instead of a movable piston, as in the former one, and the throttle valve seats on a face formed around the bottom of the balancing piston instead of on the stand pipe. Minor features of difference are that the top of the throttle valve is cast integral with the body thereof, instead of being a detachably connected plate, and the balancing piston is fitted with a packing ring, 7^a, instead of having water grooves, as in the former case. The balancing piston, 7, is, in this instance, formed integral with, or secured to, a subjacent valve seat ring, 9, which is secured, by bolts, 9^a, to the top of the stand pipe, the thereby fixed balancing piston, fitting truly in the balancing chamber within the throttle valve. A conical face, 9^b, formed on the periphery of the top of the valve seat ring, 9, constitutes the seat of the throttle valve, 3, which, with the associated pilot valve, 8, is raised and lowered, from and to its seat, in the manner hereinbefore described.

We claim as our invention and desire to secure by Letters Patent:

1. The combination of an open topped stand pipe; a throttle valve, seating at the top of said pipe and having an internal cylindrical balancing chamber; a balancing piston fitted in said chamber; and means for instituting equilibrium of pressure, in the balancing chamber, on said piston and on the throttle valve.

2. The combination of an open topped stand pipe; a throttle valve, seating at the top of said pipe and having an internal cylindrical balancing chamber; a balancing piston fitted in said chamber; a pilot valve controlling the admission of steam into said chamber; and means for successively unseating said pilot valve and the throttle valve.

3. The combination of an open topped stand pipe; a throttle valve, seating at the top of said pipe, and having an internal cylindrical balancing chamber; a balancing piston fitted in said chamber; a pilot valve controlling the admission of steam into said chamber; a valve stem carrying said valve and passing freely through the throttle valve and balancing piston; a tappet fixed on said stem, in position to abut against the throttle valve when the pilot valve is unseated; and means for imparting vertical movement to the valve stem.

4. The combination of an open topped stand pipe; a throttle valve, seating at the top of said pipe, and having an internal cylindrical balancing chamber; bearing lugs at the lower end of said chamber; a balancing piston fitted in said chamber and normally resting on said lugs; an open topped hood surrounding the throttle valve; and having vertical guide ribs fitting the periph-

ery of the throttle valve; a pilot valve controlling the admission of steam to the balancing chamber; a valve stem carrying said valve and passing freely through the throttle valve and balancing piston; a tappet fixed on said stem, in position to abut against the throttle valve when the pilot valve is unseated; and means for imparting vertical movement to the valve stem.
